UNITED STATES PATENT OFFICE

2,011,089

BLEEDER FOR DRILL STEMS

Frederick C. Smith, Jr., Houston, Tex., assignor
to Hughes Tool Company, Houston, Tex., a corporation of Texas

Application May 14, 1934, Serial No. 725,632

2 Claims. (Cl. 255—28)

My invention relates to means for bleeding the drilling fluid from the drill stem when the bit openings have become clogged.

It is a difficulty in some formations and with certain types of drills that the openings through the bit for the flushing fluid become clogged and cannot be cleared out by the usual methods. It then becomes necessary to withdraw the drill stem and drill from the well to open up the passages. This operation of withdrawing the drill stem when the openings are clogged is an unpleasant one because the mud in the drill stem cannot drain out through the clogged openings. Each section of the stem, as it is uncoupled from the sections below is full of mud which is discharged upon the derrick floor and upon those handling the tools. Furthermore, if danger of gas blowout is present, care must be taken to fill the well with mud to replace that removed with the drill stem so as to weight down the gas pressure.

It is an object of my invention to provide means to permit the fluid in the drill stem to drain out at a point adjacent the lower end thereof when the stem is withdrawn with the bit passages clogged.

I desire to provide openings in the drill stem which are normally closed, but which may be opened by means operated from the surface to allow liquid in the stem to escape as the said drill stem is withdrawn.

In the drawing, Fig. 1 is a side view partly in vertical section illustrating my invention applied to a drill stem.

Fig. 2 is a transverse section on the line A—A of Fig. 1.

The drill bit 1 shown in Fig. 1 is an ordinary fishtail bit and is merely illustrative of a type of well drill with which the invention may be used, the device being designed for use with any form of drill. The drill is formed with an upper shank 2 for engagement with a drill collar 3.

The said drill collar is of strong tubular construction with a central passage 4 therethrough for the flushing fluid which is discharged upon the bottom of the hole through outlets 5 in the bit head. The upper end of the collar 3 is formed to engage with the lowest section of drill stem 6.

My invention is preferably mounted in the drill collar but may, of course, be mounted in any of the lower drill stem couplings or tool joints, not shown.

My device includes a small metal tube 7 which I mount diametrically of the drill collar so as to close two opposite openings 8, 8. This tube is made of some material which may be easily broken or sheared off by a weighted object such as a sinker bar or ball dropped down through the drill stem from the upper end. The tube 7 is flared at its ends to engage within a flared recess 9 at each outer side of the collar and thus hold the tube in position. This flaring of the ends of the tube is accomplished by spreading the ends by means of a proper tool after said tube has been inserted through the openings 8 into position.

In operation, the tube will not interfere with the flow of liquid through the drill stem and out the openings 5 in the drill. But should the said openings 5 become clogged so as to necessitate the withdrawal of the drill, the tube 7 may be broken or sheared off to free the openings 8 in the drill collar, by dropping a heavy object such as a metal bar down the drill stem. When the tube is broken the liquid above can drain out the openings 8 as the drill stem is raised from the well in the usual manner.

The device provides means to avoid the loss of mud from the well hole when the drill stem is withdrawn. It also avoids the slopping of the mud from the drill stem sections all over the platform and upon the operators. It is simple and may be easily and economically installed.

What I claim as new is:

1. A hollow drill stem, a drill bit thereon having discharge openings therein for flushing fluid circulated downwardly through said stem, a drill collar having diametrically arranged openings, a tube connecting said openings and normally closing the same, said tube being easily broken by a shock thereon from above to allow discharge of flushing fluid through said openings.

2. A hollow drill stem, a drill bit thereon having discharge openings therethrough for flushing fluid circulated downwardly through a central passage in said drill stem, there being opposite lateral openings in said passage spaced above said drill bit, and a diametrical tube sealing therein and normally closing said openings but adapted to be rendered ineffective to close the same in response to a blow delivered thereon from above.

FREDERICK C. SMITH, JR.
